UNITED STATES PATENT OFFICE.

PEARL SHIPLEY AND KILBY FARRAR, OF LONDON, OHIO.

BOTTLE-STOPPER EXTRACTOR.

1,294,367.

Specification of Letters Patent.

Patented Feb. 11, 1919.

Application filed February 11, 1918. Serial No. 216,657.

To all whom it may concern:

Be it known that we, PEARL SHIPLEY and KILBY FARRAR, citizens of the United States, residing at London, in the county of Madison and State of Ohio, have invented cer-

tain new and useful Improvements in Bot-
tles-Stopper Extractors, of which the follow-
ing is a specification.

This invention relates to bottle stopper ex-
tractors, and has for its primary object to
provide a simple and useful tool for facil-
itating the removal of a stopper from an as-
sociated bottle neck, in a convenient and ex-
pedient manner.

Another object of the invention is to pro-
vide an extractor of this character with im-
proved means for preventing the breaking or
disintegration of a cork stopper while the
latter is being withdrawn from a bottle neck
through the use of said tool, the latter ob-
ject being chiefly accomplished through the
provision of a sliding needle member car-
ried by the tool and which is adapted to pen-
etrate the body of the stopper so that the
latter will be braced or strengthened when
the withdrawal thereof is being effected.

With these and other objects in view, as
will appear as the description proceeds, the
invention accordingly consists in the novel
features of construction, combination of ele-
ments, and arrangement of parts hereinafter
fully described in the following description
and having the scope thereof indicated in the
claim hereunto appended.

In the drawing;

Figure 1 is a side elevation of the tool or
stopper extractor comprising the present in-
vention, and illustrating the application of
the same when effecting the withdrawal of a
bottle stopper.

Fig. 2 is a perspective view of the extrac-
tor.

Similar characters of reference denote cor-
responding parts throughout the views of the
drawing.

Referring more particularly to the draw-
ing, the numeral 1 designates the tool or
stopper extractor comprising the preferred
form of the invention. The same consists, in
this instance, of a handle portion 2, which is
formed from any desired material and of
any preferred design. The lower end of the
handle is socketed, as shown, for the recep-
tion of the securing extremity 3 of a metallic
shank or web member 4. At this juncture it
is thought advisable to state that, if desired,

the handle 1 and the portion 4 may be
formed integral, however, the form of the
tool illustrated has been found in practice
to give very satisfactory service.

60

Integrally formed with the lower edge of
the shank portion 4, and situated substan-
tially centrally thereof is a curved stopper
engaging prong or claw 5, which latter has
its inner end spaced from one of the outer
edges of the portion 4 to provide a fulcrum
shoulder 6, and that part of the shank por-
tion 4 disposed on the opposite side of the
claw 5 forms a base portion 7, which is
adapted to bear upon the upper surface of 70
a cork 8.

From the foregoing it will be seen that
when it is desired to extract the cork 8 from
the neck 9 of a bottle, the portion 5 is forced
into the body of said cork until the shoulder 75
6 engages with the upper edge of the neck 9.
Then by revolving the handle 2, using the
shoulder 6 as a fulcrum, said cork may be
readily extracted from the bottle neck by
virtue of the curved formation of the por- 80
tion 5 and due to the location of the latter
within said stopper. In order to prevent the
stopper 8 from breaking or disintegrating by
reason of the pressure exerted upon the same
through the provision of the curved claw 5, 85
said shank portion 4 is provided with an
eye or bail member 10, in which is slidably
positioned a needle element 11. The latter
is secured in sliding relation with the tool
1 by forming said needle with an enlarged 90
body portion 12, in which is provided an
elongated slot 13. Carried by the handle 2 is
a headed stud 14, which is positioned with-
in the slot 13 so as to control the sliding
movements of the needle element 11. A 95
manipulating handle 15 is formed upon the
upper end of the body portion 12 and pro-
vides convenient means for effecting the re-
ciprocation of said element.

In operation after the portion 5 has been 100
inserted into the cork 8, and the shoulder
6 brought to bear upon the upper edge of
the neck 9, said needle element is then forced
into the body of the stopper 8, as shown in
Fig. 1, so as to extend adjacent to said por-
tion 5. It will now be seen that when the
handle 2 is rocked, the stopper 8 will be
reinforced or braced by the location of the
element 11, so that the breaking or disinte-
gration of said cork will be effectively pre- 105
vented. If the cork 6 happens to protrude
above the level of the neck 9, the curved un-

110

der edge of the claw portion 5 may be employed as a fulcrum in lieu of the shoulder 6, as will be clearly understood.

It will thus be seen that there is provided 5 a tool for quickly and conveniently effecting the removal of a cork from the neck of a bottle and one wherein the breaking up of a cork into sections or particles will be obviated. If desired, the shank 4 may be formed 10 with a curved finger 16, so that the tool may be employed in effecting the removal of a metallic bottle cap.

What is claimed as new and patentable is:

An extractor for bottle stoppers, comprising 15 a handle portion, a shank carried by one end of said portion, a curved stopper engaging claw formed with said shank, a bail

formed with said shank, a stopper reinforcing needle slidably mounted within said bail, said needle terminating in an enlarged body 20 portion having a manipulating handle formed therewith, and a rigid element protruding from said handle and positioned within a slot formed in said body portion for controlling the sliding movement of said 25 needle.

In testimony whereof we affix our signatures in presence of two witnesses.

PEARL SHIPLEY.
KILBY FARRAR.
